ANATOMY
(Human)

*Definition: Anatomy is the Science that Treats of the Characters, Form, Size, Function and Position of Organs and Parts of the Human Body.

†Divisions:

<u>Skeleton</u>	2
<u>Muscles</u>	2
<u>Skin</u>	3
<u>Nervous System</u>	4
<u>Circulation</u>	5
<u>Special Senses</u>	6

QUIZ

*Define Anatomy.
†What are the Divisions here analyzed?
(Ask both questions.)

Anatomy
Skeleton

2
Points

TRUNK
*56 bones

†Definition: The Body, Apart from Head and Limbs.

†Classification of Bones:

<u>Spinal Column</u>	24
<u>Ribs</u>	24
<u>Sternum</u>	1
<u>Hyoid</u>	1
<u>Pelvis</u>	4

QUIZ

*How many Bones in the Trunk?
†Define the Trunk?
†Enumerate the Trunk Bones.

Anatomy
Skeleton
Trunk

3
Points

STERNUM

1 bone

*Sternum (Breastbone)
In a Child, 6 pieces
In an Adult, 3 pieces
In Old Age, 1 piece
†Hyoid: The U-shaped Bone at Base of Tongue.
†The Hyoid is the Most Isolated Bone. No Articulation.

QUIZ

*Describe the Sternum.
†Describe the Hyoid.
†Is it Articulated?

Anatomy
Skeleton

2
Points

SKULL
* 28 bones

†Definition: The Skeleton of the Head
†Classification of Skull Bones:

<u>Cranium</u>	8
<u>Face</u>	14
<u>Ears</u>	6

QUIZ

*How many Bones in the Skull?
†Define the Skull?
†Enumerate the Skull Bones?

Inventor

Elizabeth M. Phillips,

UNITED STATES PATENT OFFICE.

ELIZABETH M. PHILLIPS, OF CLARENDON, VIRGINIA.

EDUCATIONAL CARD GAME.

Application filed September 29, 1926. Serial No. 128,378.

My invention relates to games, and more particularly to educational games in which playing cards are used, each card of each game containing questions and answers relating to a certain subject, for example, anatomy, geography, history, literature, languages, and the like. The cards of each game are divided into two or more classes, according to the importance or rank of the 10 questions and answers in relation to the main subject.

In some of the games questions and answers on the same card may have different values in marking up the score. Different 15 games or packs of cards may be made up at will by the player by segregating and playing with the cards of one or more classes from one or two or more games.

For the purpose of illustration I have 20 chosen for this particular game the subject of anatomy.

The object of the invention is to produce a game that will be entertaining and educating by impressing the subject-matter of 25 a particular game upon the mind of the players.

In the drawings forming a part of this specification, and in which like symbols of reference represent corresponding parts in 30 the several views:—

Figure 1 is an enlarged view of the face of the master card of the game;

Figure 2 illustrates a card having a different class value; and,

Figures 3 and 4 illustrate cards having another class value.

In playing the game every card of a particular class has the same value in marking up the score. Class 1, for instance, not 40 shown, have cards indicating a value of one point; class 2, illustrated by cards 11 and 12, have a value of two points each; class 3, illustrated by card 13, three points, etc. In each game is a master card, indicated by

45 14; that is, a card outlining the subject of the game and its various divisions. In marking up the score this card, having a minus value, is the least desirable card in the pack.

50 The pack of cards may consist of the usual number, or the number may be increased, if desired. In the game illustrated the study of anatomy is divided into six main groups, as shown on the master card.

55 The symbol 1 represents the skeleton; 2 the muscles; 3 the skin; 4 the nervous system;

5 the circulation; and 6 the special senses. Each of these subjects is again divided and subdivided. An underlined word indicates that there is a special card for the subject 60 underlined. Questions under "Quiz" are preceded by a mark corresponding to the mark preceding the answer to the question on the same card.

The number of players may be from three 65 to ten; and more can play by using two packs. All players are first called "students." The object of the game is to be first to win thirty points over and above losses. Any player may shuffle the cards. 70 The player to the shuffler's right cuts, leaving at least five cards in each packet. The cards are then shuffled again by the player who first shuffled them. This player becomes the dealer.

75 In dealing, one card is dealt to each player, beginning at the left, until each player has five cards, and the remainder of the pack is laid face down on the table. Each player then studies the cards in his 80 hand from one to five minutes, as may previously be agreed upon. When time is up the dealer slaps his hand on the table and calls "time." All players turn their cards face downward on the table under their hands. 85 The dealer selects any player he pleases and says, "You are first quizzer." The players again take their cards in their hands. The quizzer draws one card from the hand of the player to his left and asks said player one 90 question from the card so drawn. If the player so quizzed answers the question fully and correctly, making an intelligent use of every word in the answer which begins with a capital letter, the quizzer returns the card 95 to said player, who places it on the table in front of him. If he fails to answer the question fully and correctly the quizzer places the card, face downward, on top of the pack on the table.

100 The words of a single question under quiz, when taken alone may not convey the full meaning of the question; therefore, the quizzer will use his intelligence and make each question clear to the player who is 105 being quizzed. All words beginning with a capital letter must be properly used in the answer.

110 The master card, illustrated in Figure 1, is an exception to the above play. The quizzer asks both questions on the master card, one at a time, and if the player quizzed

fails to answer one or both fully and correctly, the quizzer returns the card to the player, who places it on the table in front of him. The possession of this card when score is taken means a loss of five points. If the questions are answered correctly the quizzer places the card face downward on top of the pack.

The player last quizzed becomes the next ¹⁰ quizzer, draws a card from and asks a question of the player to his left, and the play proceeds around the same as before until all the cards have been drawn from the hands of the players. The score is kept by the ¹⁵ dealer, who marks up for each player the points lost or won by each player, as indicated by the cards in front of him at end of the hand. Every player who has gained at least ten points has earned the title of ²⁰ "tutor." Twenty points gives the title of "professor." The first player to win thirty points wins the game and becomes "president of the college." This ends the game.

Until some player has won the game by ²⁵ making thirty points, all the cards, including the pack on the board, are shuffled and dealt as at first, the winner becoming the dealer, and the play proceeding as above until some player has won thirty points and ³⁰ the game.

Having now fully described my invention, what I claim as new, and desire to secure by Letters Patent, is:—

1. An educational game, comprising a series of cards having questions and answers on the same card, relating to different subjects, each of said cards indicating a certain value, and marks identifying the questions with the answers.

2. An educational game, comprising a series of cards having questions and answers on a particular subject, means identifying the questions with the answers, and a master card comprehending all the subjects. ⁴⁰

3. An educational game, comprising a series of cards, each having questions and answers relating to a particular subject, a master card comprehensively outlining the general subjects of the other games, and each card having reference marks or other ⁵⁰ means of connecting the questions with the corresponding answers.

4. An educational game, comprising a master card outlining the subject of the game, a series of cards divided into two or ⁵⁵ more classes according to rank and having different values, certain words on some of the cards being marked to indicate reference to certain other cards.

5. An educational game, comprising a master card outlining the subject of the game, a series of cards divided into different classes having different values, each card of a particular class having the same value in marking the score, and marks on the cards ⁶⁵ to indicate the subjects and the relationship of the different cards.

6. An educational game, one of a number of similar games, comprising a series of cards with questions and answers, said cards ⁷⁰ having different values, each card of each series having a specific value, the different series being adapted to be interchangeable with the series of the same value in other games. ⁷⁵

In testimony whereof I affix my signature.

ELIZABETH M. PHILLIPS.
